UNITED STATES PATENT OFFICE.

NATHAN ADAMS, OF ALTOONA, PENNSYLVANIA.

IMPROVEMENT IN SPIKE-EXTRACTORS.

Specification forming part of Letters Patent No. 128,996, dated July 16, 1872.

Specification describing certain Improvements in Machines for Drawing Spikes and Bolts, invented by NATHAN ADAMS, of Altoona, in the county of Blair and State of Pennsylvania.

My invention relates to the combination of a lever and toggle-catch with a fulcrum-box having inclines which support the fulcrum-pins of the lever—the inclines being so constructed and arranged as to admit of an automatic changing in the position of the fulcrum-pins as the grasping points of the lever and toggle-catch ascend in the withdrawal of the bolt, as hereinafter fully described.

Figure 1 is a plan view of the machine placed on a piece of timber. Fig. 2 is a side elevation of the same.

Like letters in both figures indicate the same parts.

A is a piece of timber, and B a bolt which is being withdrawn. C is a box open at bottom and top. The box I prefer making of steel. The side pieces a a are connected at their ends by means of the screw-bolts b b. D is a lever which is provided with a fulcrum-pin, E, its ends d d projecting outward from the sides of the lever and connecting with inclined slots e e in the sides of the box C. F is a toggle-catch hung on the bolt b opposite the lever, so that when the box is placed over

a bolt, B, and the grasping points f and f' of the lever and toggle-catch are caught against opposite sides of the bolt, as represented in the drawing, by the manipulation of the lever as its point f rises in the withdrawal of the bolt, the point f' of the toggle-catch also rises, the catch turning freely on the bolt b, and the projecting ends d d of the fulcrum-pin E automatically changing their position in the slots e e in accommodation thereto. When the point f of the lever is released from the bolt to take a new grasp, the catch falls down to its lower position, as represented, to act with the lever in a further withdrawal of the bolt. By a continued repetition in the up-and-down movements of the lever and toggle-catch, which may be made with great rapidity, as the movements of the toggle-catch are automatic with those of the lever, the bolt or spike is withdrawn.

I claim as my invention—

The fulcrum-box C, having inclined slots e e, in combination with the lever D and toggle-catch F, substantially in the manner and for the purpose above described.

NATHAN ADAMS.
